UNITED STATES PATENT OFFICE.

GEORGE MACKAY, OF ROCHESTER, NEW YORK.

DESIGN FOR BOTTLE.

Specification forming part of Design No. 7,832, dated November 3, 1874; application filed October 24, 1874.
[Term of Patent 7 years.]

To all whom it may concern:

Be it known that I, GEORGE MACKAY, of the city of Rochester, in the county of Monroe and State of New York, have invented a new and original Design for Bottles; and I do hereby declare that the following is a full, clear, and exact description of the same, reference being had to the accompanying drawing, in which the figure represents a perspective view of the bottle.

This bottle is intended to hold what is known as "Mackay's Hoof Ointment," a compound for the treatment of horses' feet.

The design consists in forming the bottle in the shape of a horse's hoof and ankle, as hereinafter described.

A is the bottom of the bottle, which is in the form of the hoof. B is the body of the bottle, which is in the form of the ankle. The

body has a swell, a, which is in the form of the ankle joint, and at the rear is a projection, b, which represents the fetlock.

The whole outline is such as to represent, as nearly as possible, the hoof and ankle of a horse.

At the top is a rim, c, which surrounds the mouth of the bottle.

What I claim as my invention is—

The design for a bottle in the form of a horse's hoof and ankle, as herein shown and described.

In witness whereof I have hereunto signed my name in the presence of two subscribing witnesses.

GEORGE MACKAY.
